CHEMICAL PROCESS

Walter C. Menly, Highland Park, N. J., assignor
to E. I. du Pont de Nemours & Company, Wil-
mington, Del., a corporation of Delaware

No Drawing. Application February 17, 1942.
Serial No. 431,315

9 Claims. (Cl. 260—397.2)

This invention relates to the production of organic polynuclear compounds and more particularly to the production of provitamins D. Still more particularly it relates to the production of doubly unsaturated steroids, characterized by having two conjugated double bonds in ring II of the cyclo-pentano-perhydro-phenanthrene nucleus. Still more particularly it relates to novel methods for removing acid groups from esters of 7-hydroxy sterols whereby 7-dehydro 10 sterol compounds are formed.

Certain 7-dehydro sterol compounds are quite commercially important compounds, for example, the 7-dehydro-sterols are quite valuable provitamins D and can be antirachitically activated to produce vitamin D. Among the useful sterols are 7-dehydro-stigmasterol, 7-dehydro-cholesterol, and 7-dehydro-sitosterol. The preparation of these compounds from the corresponding 7-hydroxy sterol esters by various manners has been described in various patents and literature references.

In U. S. P. 2,098,984, the thermal decomposition of diesters of 7-hydroxysterols with monocarboxylic acids at elevated temperatures under reduced pressures is described whereby 7-dehydrosterol carboxylic acid esters are formed. The monoesters are saponified to form 7-dehydrosterols. U. S. P. 2,209,934 describes the production of 7-hydroxysterols from diesters of 7-hydroxy-sterols with monocarboxylic acids by reacting them with organic nitrogen bases followed by the saponification of the 7-dehydrosterol ester formed. U. S. P. 2,255,815 describes the treatment of such di-esters with organic salt forming compounds in the presence of oxonium salt forming compounds and also additional materials. These procedures have a number of advantages but also have some disadvantages. For instance, they require careful control and supervision, the yields are sometimes low with uneconomical by-product formation, the assistants are expensive and sometimes relatively unavailable.

This invention has for an object, a new method of removing carboxylic acid groups from esters of Δ 5,7-hydroxy steroids with monocarboxylic acids. A further object is to provide such a method using readily available and relatively inexpensive material. A still further object is to provide such a process which involves a simple procedural step. Another object is to provide such a process which can be carried out in simple and economical apparatus. Still other objects will be apparent from the hereinafter described invention.

It has now been found that 7-dehydro-steroids can be obtained in an economical manner from Δ 5,7-hydroxy steroid esters wherein the 7-hydroxyl group is esterified with a monocarboxylic acid by heating such esters in the presence of an excess of a hydrocarbon until said steroid ester is converted into the 7-dehydro form. The resulting compounds as a rule crystallize out from the reaction mass in a state of high purity but they may be further purified by crystallization, etc., or converted into derivates. In the case of the diesters of Δ 5,7-hydroxy sterols and organic monocarboxylic acids, the 7-dehydro-sterol esters thus formed may be converted into 7-dehydro-sterols by reacting them with saponifying agents.

It has further been found that the yield of the desired 7-dehydrosterol can be substantially increased if the amount of hydrocarbon solvent employed is a multiple of the weight of the 7-hydroxycholesterol diacyl ester. Thus I find it advantageous to employ from 5 to 100 parts of hydrocarbon solvent for each part of ester.

A further aspect of this invention is embodied in the carrying out of the reaction under such conditions of temperature and pressure that the hydrocarbon solvent is at its boiling point and that a portion thereof is continually being distilled off and removed from the seat of reaction.

The marked improvement in yield of the desired 7-dehydro-sterols obtainable by employing either multiple parts of hydrocarbon solvent or removal by distillation of part of the hydrocarbon solvent during reaction, may be ascribed to the fact that under the conditions aforementioned, the concentration of liberated monocarboxylic acid in the reaction mass is kept very low at all times, due either to high dilution or to removal by distillation with hydrocarbon solvent. While the above explanation may account at least in part for the high yields obtained, neither the high dilution nor the distillation of the hydrocarbon solvent are essential steps of the invention.

According to one practical aspect of the invention, 7-dehydro-sterol compounds are obtained in high yields by heating Δ 5,7-hydroxysterol esters to a temperature between 150° C. and 250° C. while they are uniformly dissolved or dispersed in 5 to 100 times their weight of hydrocarbons. The pressure may be atmospheric or sub-atmospheric or super-atmospheric. After cooling, the larger part of the hydrocarbon is removed by distillation, if necessary under diminished pressure, and the desired 7-dehydrosterol ester will crystallize in a state of high purity. The 7-de-

hydro-sterol esters can be directly converted to 7-dehydro-sterols by first extracting the acid formed and then adding a saponifying agent to the hydrocarbon mixture and reacting the same with the 7-dehydro sterol ester to form 7-dehydro-sterols. The acid formed can be extracted in like manner, the hydrocarbons distilled off and the sterol purified by crystallization.

In a preferred aspect of the invention, stable, normally liquid hydrocarbons (i. e., hydrocarbons which are liquid at atmospheric pressure at temperatures in excess of 150° C.) are used under conditions such that at least 10 parts of hydrocarbon is at all times present with the Δ5,7-hydroxy steroid esters. The temperature is preferably chosen so that the reaction will go to completion in 1 to 10 hours.

The heating can be carried out in various manners by heating the Δ5,7-hydroxy steroid esters dissolved or dispersed in the hydrocarbon in a vessel which is provided with means for refluxing the vapors or for sealing the same. Agitating means can be provided to insure a uniform distribution and prevent local overheating. Jackets for introducing a heating medium, e. g. water, oil, steam, etc., may be provided or the vessels may be heated by direct fire.

The invention will be further illustrated but is not intended to be limited by the following examples wherein the parts stated are parts by weight unless otherwise specified:

Example I

One hundred parts of 7-hydroxycholesterol dibenzoate melting point 173-174° C. and 1000 parts of tetralin (tetrahydronaphthalin) are heated in a vessel provided with a reflux condenser. The ester goes in solution as soon as the temperature is raised. The solution is heated rapidly to the boiling point of tetralin (210-215° C.) and maintained for 2 hours at reflux temperature. An analysis for benzoic acid indicates that the solution contains 2.0%-2.5% benzoic acid. After cooling the solution to about 100° C. vacuum is applied and most of the tetralin is removed by distillation. Upon cooling the desired 7-dehydrocholesterol benzoate will crystallize out. The crystallization may be improved by the addition of a non-aromatic low boiling solvent such as methyl alcohol, acetone and the like which promote complete precipitation of the desired product. The benzoic acid formed will stay in solution. After filtration there are obtained 60-70% of 7-dehydrocholesterol benzoate of excellent purity.

Example II

One hundred parts of 7-hydroxycholesterol dibenzoate and 200 parts of tetralin are heated in a vessel provided with a reflux condenser after the manner set forth in Example I. The 7-dehydrocholesterol benzoate is recovered and purified after the manner described in Example I. A yield of 48% of 7-dehydrocholesterol is obtained. The concentration of benzoic acid present at the end of the reaction is about 8%.

Example III

One hundred parts of 7-hydroxycholesterol dibenzoate and 200 parts of tetralin are heated in a vessel so that the tetralin distills over at a slow rate requiring about 2 hours to distill over most of the tetralin. The small amount of tetralin remaining in the vessel is cooled and the 7-dehydrocholesterol benzoate recovered and purified if desired after the manner set forth in Example

I. The tetralin concentrate will contain crystals of benzoic acid which can be recovered in any desired manner.

Example IV

One hundred parts of 7-hydroxycholesterol dibenzoate are heated with 600 parts of naphthalene to a temperature of 200-220° C. for a period of 3 to 6 hours. After removal of most of the naphthalene in a manner similar to that described in Example I there are obtained about 50% of pure 7-dehydrocholesteryl benzoate.

Example V

In a closed vessel 20 parts of 7-hydroxycholesterol dibenzoate admixed with 400 parts of a petroleum hydrocarbon fraction boiling around 120° C. at ordinary pressure, are heated to about 230° C. for a period of 2 to 6 hours. After cooling, the reaction product is extracted with an aqueous solution of sodium carbonate in order to remove the benzoic acid formed. To the remaining hydrocarbon solution a solution of alcoholic potassium hydroxide is added and the solution is refluxed for one hour to saponify the 7-dehydrocholesterol benzoate which has been formed. The saponification mass, after cooling, is extracted with water and the remaining hydrocarbon solution is subjected to distillation under reduced pressure until about 100 parts of solvent are left. The residue is cooled whereby 7-dehydrocholesterol crystallizes out in a yield of 40-50%.

In place of the specific hydrocarbon set forth in the above examples there may be substituted a wide variety of hydrocarbons which have the above described characteristics. The useful hydrocarbons are not limited to any one particular type, on the contrary, simple and mixed aliphatic, cycloaliphatic, alicyclic, aromatic and aliphatically substituted aromatic hydrocarbons which are stable at the reaction temperature, can be used. The hydrocarbons may be substituted by innocuous groups such as chlorine, fluorine, etc.

As examples of suitable additional hydrocarbons mention is made of cyclohexane, methylcyclohexane, ethylcyclohexane, benzene, toluene, xylene, naphthalene, dihydronaphthalene, decahydro-naphthalene; pinene; heptane, octane, etc., petroleum ether, benzine, ligroin as well as high boiling mineral oil fractions; halogenated hydrocarbons, e. g., dichloroethane, tetrachloroethane, chlorobenzene, dichlorobenzenes, chlorotoluene, chlorotrifluoride, etc.

The quantity of hydrocarbon may be varied over a fairly wide range, e. g., from 1 to 100 parts of hydrocarbon per part of steroid ester. In general, higher yields are obtained by the use of an excess of hydrocarbon. A preferred range is 5 to 25 parts of hydrocarbon per part of steroid ester.

The temperature and time may also be varied over a fairly wide range, e. g., from 150° C. and less to 300° C. and over. A temperature from 160° C. to 260° C. represents a preferred range. The time may vary from about 2 hours to 16 hours and over depending somewhat on the temperatures employed. For example, 2 hours heating at 220° C., 6 hours at 200° C. and 16 hours at 180° C., give substantially the same yields. It is not necessary, however, to convert all the diester to the 7-dehydro compound. The reaction may be cut short when partially complete. It may be conducted somewhat continuously by drawing off and crystallizing formed 7-dehydro compounds and replenishing the reaction mixture.

It should be understood that the invention is

not limited to the treatment of the specific Δ 5,7-hydroxy-sterol esters described in the working examples. On the contrary, it embraces the treatment of steroids generally wherein a double bond exists in the Δ 5,6-position regardless of whether additional substituents are also present in other positions in the molecule. Any ester compound having the cyclo-pentano-perhydro-phenanthrene skeleton may be used wherein the ester group is in the 7-position and a double bond is in the 5,6-position. Such substances are sometimes termed steroid or sterid compounds and include those having the nucleus referred to with or without side chains including said chains with other functional groups such as oxo, hydroxyl and carboxyl groups and their derivatives. Thus, the term "steroids" includes not only sterols, but also bile acids, plant heart poisons, saponines and sex hormones. Among the suitable polyesters of the above-described types are beta-7-hydroxy-cholesterolesters, 7-hydroxy-sitosteryl diesters, 7-hydroxy stigmasterol diester, 3,7 - dihydroxy - 5 - chioenic acid esters, 5-androstentriol-3,7,17-triesters, and the corresponding esters of pregnane series. Still other suitable esters include the simple or mixed carboxylic esters of 7-hydroxy sterol compounds obtainable from acids such as nitrobenzoic, m-dinitrobenzoic, chlorobenzoic, toluic, phenylacetic, cinnamic, formic, propionic, butyric, valeric, etc., acids or their acid anhydrides and acid halides, e. g., acyl chlorides. Any of the diesters disclosed in U. S. Patents Nos. 2,209,923 and 2,215,727, for instance, may be used as starting materials in the present processes.

The 7-dehydro steroid esters can be converted into 7-dehydro steroids containing hydroxyl groups in the 3-position in various manners. For example, they may be saponified by means of a caustic alkali metal hydroxide in alcoholic solution. Alkaline earth metal hydroxides may be used in ethyl alcohol solutions if desired.

This invention has a number of advantages in that it enables one to obtain 7-dehydro-sterol compounds from esterified 7-hydroxy sterols in a simple manner. A further advantage resides in the fact that the hydrocarbons are relatively inexpensive as compared with acid binding agents which have been previously prepared. Another advantage is that the hydrocarbons are odorless, relatively non-toxic and can be discarded after the use without constituting an economic loss.

The use of the hydrocarbons has an additional advantage that it enables acids to be removed from the esterified steroids without the necessity of resorting to a high degree of vacuum. In addition, the hydrocarbons form a practical medium for saponifying ester groups in the 3-position of a sterol nucleus whereby sterols are formed.

As many apparently widely different embodiments of this invention may be made without departing from the spirit and scope thereof, it is to be understood that I do not limit myself to the specific embodiments herein except as defined by the appended claims.

I claim:

1. The process which comprises heating a

steroid characterized by having an esterified hydroxyl group in the 7-position and a double bond in the 5,6-position of a cyclo-pentano-perhydro-phenanthrene nucleus, which is maintained in a liquid hydrocarbon medium until a material amount has been converted into the 7-dehydro form.

2. The process which comprises heating a steroid characterized by having an esterified hydroxyl group in the 7-position and a double bond in the 5,6-position of a cyclo-pentano-perhydro-phenanthrene nucleus, which is dispersed in an excess of a liquid hydrocarbon medium to a temperature from about 150° C. to about 300° C. until a material amount has been converted into the 7-dehydro form, removing the acid formed and recovering the 7-dehydrosteroid.

3. The process which comprises heating a diester of a 7-hydroxy sterol which contains a monocarboxylic acid ester group in the 7- and 3-positions, dispersed in from 5 to 25 parts by weight of a liquid hydrocarbon per part of diester to a temperature from 150° C. to 300° C. until a material amount has been converted into a 7-dehydro-sterol monoester.

4. The process which comprises heating a diester of a 7-hydroxy sterol which contains a monocarboxylic acid ester group in the 7- and 3-positions, dispersed in a liquid hydrocarbon medium to a temperature from 150° C. to 300° C. for a period of at least 2 hours and recovering the 7-dehydro sterol monoester.

5. The process which comprises admixing an esterified 7-hydroxy sterol with a stable, liquid hydrocarbon of low viscosity having a boiling point from 150° C. to 250° C. and heating the resulting mixture to a temperature from about 150° C. to 300° C. for a period of at least 2 hours.

6. The process which comprises admixing an esterified 7-hydroxy sterol with an excess of a stable hydrocarbon having a boiling point from 150° C. to 250° C. and heating the resulting mixture to a temperature from 150° C. to 300° C. until a material amount of said esterified sterol has been converted into a 7-dehydro-sterol monoester, recovering the acid produced and converting the monester into a 7-dehydro sterol.

7. A process which comprises admixing a mol of a diester of a 7-hydroxy-sterol and a mono-basic carboxylic acid with from 5 to 25 parts by weight of a stable hydrocarbon per part of diester and heating the resulting mixture to a temperature sufficient to split off a carboxylic acid group until a material amount of said esterified sterol has been converted into a 7-dehydro monoester.

8. The process which comprises heating a diester of 7-hydroxy-cholesterol in the presence of a hydrocarbon which is liquid at room temperature, in order to produce a substantial amount of 7-dehydro-cholesterol ester.

9. The process which comprises heating one part by weight of 7-hydroxy-cholesterol dibenzoate in the presence of from 5 to 25 parts by weight of tetralin to a temperature approximating the boiling point of tetralin for a sufficient period of time to produce a substantial amount of 7-dehydro-cholesterol benzoate.

WALTER C. MEULY.
